UNITED STATES PATENT OFFICE.

BERTRAND B. KAHN, OF CINCINNATI, OHIO, ASSIGNOR TO THE ESTATE STOVE COMPANY, OF HAMILTON, OHIO.

COOKING-STOVE.

1,168,510.

Specification of Letters Patent.

Patented Jan. 18, 1916.

Application filed August 9, 1915. Serial No. 44,397.

To all whom it may concern:

Be it known that I, BERTRAND B. KAHN, a citizen of the United States, residing at Cincinnati, Hamilton county, Ohio, have 5 invented certain new and useful Improvements in Cooking-Stoves, of which the following is a specification.

This invention pertaining to cooking stoves relates to a stove of duplex character 10 designed for the use of either solid fuel or gas, and the invention will be readily understood from the following description taken in connection with the accompanying drawings in which:—

15 Figure 1 is a plan of a duplex cooking stove exemplifying my invention, the grid work over the gas burners in the top burner chamber being omitted: Fig. 2 a front elevation of the same: Fig. 3 a vertical longitudinal section of the stove in the plane of line *a* of Figs. 1, 4, 6 and 9: Fig. 4 a horizontal section in the plane of line *b* of Figs.

20 2, 3, 5 and 7, the oven burner being omitted: Fig. 5 a rear view of the stove: Fig. 6 a horizontal section of the stove in the plane of line *c* of Figs. 2, 3, 5, 7 and 8, the dampers in the upper portion of the stove being omitted: Fig. 7 a vertical transverse 25 section of a portion of the structure in the plane of line *d* of Figs. 1, 2, 3, and 5: Fig. 8 a transverse section of the structure in the plane of line *e* of Figs. 1 and 6: and Fig. 9 a vertical transverse section of the structure in the plane of line *f* of Figs. 2, 3 and 4.

30 35 Before describing the features of construction constituting the present improvements, I will describe those features designed for the utilization of solid fuel and constituting a fundamental structure which 40 is modified in view of the improvements. A diversity of scales is employed in the drawings.

In the drawings, giving present consideration mainly to Fig. 3:—1, indicates the general stove structure: 2, the extreme top: 3, the extreme bottom: 4, the fire-box: 5, the grate at the base of the fire-box: 6, the ash-pit: 7, the oven: 8, the vertical wall separating the oven from the fire-box and 45 50 ash-pit: 9, the main top of the oven: 10, the main floor of the oven: 11, the outlet to the chimney: 12, the horizontal flue

formed at the top of the oven between the main top of the oven and the main top of the stove: 13, a vertical flue at that portion 55 of the oven farthest from the fire-box and leading downward from about the level of the top of the oven to below the oven: 14, a horizontal flue leading under the oven from flue 13: 15, a port leading from flue 12 60 into the outlet to the chimney: 16, a damper to open or close this port: 17, a port through the rear wall of the stove placing horizontal flue 14 in communication with the outlet to the chimney: 18, a deflector disposed transversely in flue 14 and leading forward from the back of the stove to a point about halfway to the front of the stove: 19, a handle for controlling damper 16: 20, the outer wall of flue 13: 21, a partition disposed in 70 flue 12 and extending from the front to the rear of that flue, this partition being disposed at a point between flue 13 and the outlet 15 to the chimney.

Assume, now, for the present, that partition 21 was disposed vertically over wall 20 and that flue 13 was open at its upper end so as to be in communication with flue 12. In such case there would be presented the ordinary construction of cooking stoves in which 75 the products from the fire-box may pass around the major portion of the oven, to heat the oven, or, alternatively, may be given a direct outlet from flue 12 into the outlet to the chimney. If, under the conditions assumed, damper 16 were closed, then the hot products from the fire-box would pass through flue 12 to and through flue 13 and through bottom flue 14 and then through port 17 to the outlet to the chimney. 80 The products in passing through bottom flue 14 are caused to move toward the front of the stove and then backward to port 17. If, however, damper 16 be opened, then the products, taking the 85 path of least resistance, go direct to the outlet to the chimney through port 15 instead of passing around the oven. All of this under the assumed construction, would be the same as is common in cooking stoves, 90 and the features thus far referred to may be as usual and subject to such modification of structure as is consistent with the improvements to be later explained. But while it

has been assumed, for the purpose of preliminary understanding, that the righthand end of flue 12 communicated directly with the top of flue 13, a consideration of Fig. 5 3 will show that flue 12 does not extend sufficiently to the right to be over the top of flue 13, and that the upper end of flue 13 is closed. Wall 21 closing the righthand end of flue 12 is given the general position 10 indicated for purposes which will be later explained and has brought about the necessity for an unusual system of communication between flues 12 and 13.

Proceeding with the drawings:—22, indicates a vertical flue structure disposed at the back of the stove and constituting the communication between ports 15 and 17 and chimney outlet 11: 23, a flue-box disposed at the rear of the stove between flue structure 20 22 and wall 20: and 24, a port leading from flue 12 back into flue-box 23: and 24^a, a port leading from flue-box 23 into the upper portion of flue 13.

When solid fuel is being burned, the hot 25 products from the fire-box pass to the right through flue 12 and then pass rearwardly through port 24 and into flue-box 23 and thence through port 24^a to flue 13 and thence through horizontal flue 14 to port 30 17 leading to the chimney outlet. Aside from the peculiarities of construction the functional result is substantially the same as usual, the only difference being that in the present construction the products passing 35 from the fire-box do not pass over the entire top of the oven, the current being arrested and turned into port 24 by partition 21.

The novel flue construction which has 40 thus far been referred to, has been brought about by the desire to have a top burner box overlapping the oven, and this feature will now be explained.

Proceeding with the drawings:—25, indicates a top burner-box overlapping the top 45 of the oven and having its lefthand wall formed by partition 21: 26, burners and burner pipes disposed within the burner-box, four cooking burners and one simmering 50 burner being illustrated: 27, a port leading through the back wall of the burner-box and into flue-box 23: 28, a damper for opening and closing this port: 29, the handle for controlling the damper 28: 30, the gas supply pipe for supplying burners 26: and 31, the mixers and cocks pertaining to burners 26.

In using solid fuel damper 28 may be closed to prevent products going into the 60 burner-box and thence to the kitchen, if the burner-box has a grided top. When gas is employed in burner-box 25 dampers 28 and 16 are to be open so that the products from the burner-box may go through port 27 and 65 flue-box 23 and port 24 and flue 12 and

through port 15 to the chimney. If damper 28 be closed then the products from the burner-box will find their way to the chimney through flues 13 and 14 and port 17.

It is to be understood that the top of the 70 burner-box will be provided with the usual grid work for sustaining vessels, &c., over the burners. Looking at Figs. 1 and 2 and giving consideration to such portions of the structure as do not include the overhang of 75 the burner-box it will be apprehended that the dimensions of such structure are substantially such as would be involved in a stove for burning solid fuel and provided with six pot-holes in its top. In my construction I have abandoned two of the pot-holes which would be present in the above assumed case and have utilized the space by causing the inner portion of the burner-box to overlap the oven, the balance of the 80 85 burner-box projecting outwardly from the general structure and being supported on brackets.

It is my preference that vertical flue 22 and flue-box 23 be extraneous structures secured at the rear of the main body of the stove, though this is not essential.

I provide an oven burner for heating the oven when gaseous fuel is employed and will now explain this feature. Proceeding 90 with the drawings:—32, indicates a burner-pit in the base of the oven between wall 8 and the lefthand end of flue 14, this pit extending from floor 10 of the oven to bottom-plate 3 of the stove: 33, a pivoted cover for 95 the burner-pit, adapted, when in closed position, to complete the floor of the oven over the burner-pit: 33^a, an oven-burner disposed in the burner-pit: 34, air ports leading through the bottom of the stove and into 100 the burner-pit: 35, a valve-plate adapted to close these air ports, the plate being illustrated as being opened and closed by a hinging motion: 36, the mixer and cock for the 105 oven burner: 37, the gas supply-pipe for the oven burner: 38, a movable plate disposed in the base of the oven above floor 10 of the oven at a little distance above said floor and extending over the burner-pit: 39, insulating material, as a sheet of asbestos, secured to the lefthand portion of plate 38: 40, a series of ports or an equivalent slot extending along the righthand edge of plate 38: 41, a sub-roof in the oven at a little distance 110 below roof 9: 42, ports through each side edge of the sub-roof: 43, a flue formed between the main roof 9 of the oven and sub-roof 41 and in communication with the oven 115 through ports 42: 44, a port leading from flue 43 into flue structure 22 which flue structure is in communication with the chimney outlet: 45, a bellcrank lever connected with valve-plate 35 and adapted, when plate 38 120 is pushed into place in the oven, to open valve-plate 35: 46, a valve adapted to open 125 130

and close port 44 which places flue 43 in communication with the chimney outlet 47, arm connecting valve 16 with valve 46 in such manner that they will open and close 5 in unison; and 48, an aperture in cover 33 to engage lever 45 and hold air-ports 34 closed so long as the cover is down.

Looking at Fig. 3, and assuming that gas is to be employed in heating the oven, plate 10 38, which is not otherwise needed, is to be put in place and when it reaches its rear-most position it opens valve-plate 35 and admits secondary air to the burner-pit. The oven-burner, having been lighted, causes 15 hot products to move to the right through the passage formed between plate 38 and main floor 10 of the oven. The products pass up into the oven through ports 40 and move out of the oven through ports 42 and 20 thence through port 44 to the outlet to the chimney. As the lefthand portion of plate 38 is apt to be excessively hot, by reason of being disposed over the oven-burner, the insulating material 39 is designed to neutralize 25 this excessiveness of heat. Plate 38 may, if desired, be allowed to remain in the oven at all times, regardless of whether the oven is being heated by gas or solid fuel, but the presence of the plate detracts from the vertical dimension of the oven. When cover 30 33 is turned up to open the top of the burner-pit it is held in that position by plate 38, and upon the withdrawal of plate 38 the cover falls to its normal position as a continuation of oven floor 10.

Port 44 which permits the products from the oven to pass to the outlet for the chimney might be permitted to remain always open, but I have found, in practice, that if 40 this port 44 be constantly open it will permit undesirable escape of heated air from the oven and also detract somewhat from the effect of the draft in drawing hot products from the fire-box around the oven. 45 It is for this reason that I connect dampers 16 and 46, so that when damper 16 is closed to cause the products from the fire-box to pass around the oven the valve 46 cuts off communication between the oven and the chimney.

50 I have referred to the top burner-box as being provided in its top with the usual grid-work for the support of cooking vessels, but it should be understood that when natural gas is employed, instead of artificial gas, the top of the burner-box should be closed by a solid top provided with pot-holes.

In order to distinguish between the multiplicity of flues found in the structure, I will 60 call flue-structure 22 the "chimney-flue" as its sole office is to place various other flues or spaces in communication with the outlet to the chimney, and I will call flue 13 the "vertical flue," and I will call flue 12 the

"top flue," and I will call flue 14 the "bottom flue," and I will call flue-box 23 the "flue-structure."

I claim:

1. A cooking stove comprising, an oven, 70 a fire-box, a top burner-box overlapping the oven, a top flue extending from the fire-box over such portion of the oven as is not overlapped by the burner-box, a vertical flue extending down the side of 75 the oven on the side opposite the fire-box, a bottom flue communicating therewith and passing under the oven, a chimney-flue connected with the outlet to the chimney, a port placing the chimney-flue in communication with the bottom-flue, a port placing the chimney-flue in communication with the top flue, a damper adapted to open and close communication between the top flue and the chimney-flue, and a flue-structure disposed 80 at the back of the stove in communication with the top flue and with the upper portion of said vertical flue, combined substantially as set forth.

2. A cooking stove comprising, an oven, 90 a fire-box, a top burner-box overlapping the oven, a top flue extending from the fire-box over such portion of the oven as is not overlapped by the burner-box, a vertical flue extending down the side of the oven on the 95 side opposite the fire-box, a bottom flue communicating therewith and passing under the oven, a chimney-flue connected with the outlet to the chimney, a port placing the chimney-flue in communication with the top flue, a bottom flue, a port placing the chimney-flue in communication with the top flue, a damper adapted to open and close communication between the top flue and the chimney-flue, a flue-structure disposed at the back of 100 the stove in communication with the top flue and with the upper portion of said vertical flue, and a port placing the burner-box in communication with the flue-structure, combined substantially as set forth. 110

3. A cooking stove comprising, an oven, a fire-box, a top burner-box overlapping the oven, a top flue extending from the fire-box over such portion of the oven as is not overlapped by the burner-box, a vertical flue 115 extending down the side of the oven on the side opposite the fire-box, a bottom flue communicating therewith and passing under the oven, a chimney-flue connected with the outlet to the chimney, a port placing the chimney-flue in communication with the bottom flue, a port placing the chimney-flue in communication with the top flue, a damper adapted to open and close communication between the top flue and the chimney-flue, 120 a flue-structure disposed at the back of the stove in communication with the top flue and with the upper portion of said vertical flue, a port placing the burner-box in communication with the flue-structure, and a 130

damper adapted to close communication between the burner-box and flue-structure, combined substantially as set forth.

4. A cooking stove comprising, an oven, a fire-box at one side of the oven, a top flue extending from the fire-box over the oven, a vertical flue extending down the side of chimney-flue, a burner-pit formed between and in communication with said top flue, a bottom flue communicating with the vertical flue and passing under the oven and having an end wall near the wall dividing the oven from the fire-box, a chimney-flue connected with the outlet to the chimney, a port placing the chimney-flue in communication with the bottom flue, a port placing the chimney-flue in communication with the top flue, a damper adapted to open and close communication between the top flue and the chimney-flue, a burner-pit formed between the end wall of the bottom flue and the wall dividing the oven from the fire-box and floored by the extreme bottom of the stove and open at its top into the oven, a burner disposed therein, a plate disposed in the base of the oven above the main floor of the oven and extending over said main floor and over the burner-pit and leaving a space between the plate and the main floor of the oven and provided with ports placing said space in communication with the oven at its side opposite the burner-pit, and a port placing the extreme top of the oven in communication with the chimney flue, whereby heated products rising from the burner-pit pass upwardly the full height of the oven and then out of the oven, combined substantially as set forth.

5. A cooking stove comprising, an oven, a fire-box at one side of the oven, a top flue extending from the fire-box over the oven, a vertical flue extending down the side of the oven on the side opposite the fire-box and in communication with said top flue, a bottom flue communicating with the vertical flue and passing under the oven and having an end wall near the wall dividing the oven from the fire-box, a chimney-flue connected with the outlet to the chimney, a port placing the chimney-flue in communication with the bottom flue, a port placing the chimney-flue in communication with the top flue, a damper adapted to open and close communication between the top flue and the chimney-flue, a burner-pit formed between the end wall of the bottom flue and the wall dividing the oven from the fire-box and floored by the extreme bottom of the stove and open at its top into the oven, a burner disposed therein, a hinged cover disposed over the burner-pit and adapted to fold up against the side-wall of the oven, a plate disposed in the base of the oven above the main floor of the oven and extending over said main floor and over the burner-pit and

leaving a space between the plate and the main floor of the oven and provided with ports placing said space in communication with the oven at its side opposite the burner-pit, and a port placing the upper portion of the oven in communication with the chimney-flue, combined substantially as set forth.

6. A cooking stove comprising, a general stove structure, an oven, a fire-box at one side of the oven, a flue extending from the fire-box over the oven and down outside the oven at the side opposite the fire-box and under the oven and having an end wall near the wall dividing the oven from the fire-box, a port placing the chimney-flue in communication with the upper portion of said flue passing around the oven, a port placing the chimney-flue in communication with the bottom portion of said flue passing around the oven, a burner-pit formed between the end wall of the bottom flue and the wall dividing the oven from the fire-box and floored by the extreme bottom of the stove and open at its top into the oven, a cover hinged at the floor of the oven and adapted to form a portion of the floor of the oven or to be turned up against the wall dividing the ash-pit from the oven, and a removable plate disposed in the base of the oven above the main floor thereof and extending over said main floor and over the burner-pit to a point a sufficient distance from the wall dividing the oven from the fire-box to permit of the presence of said hinged cover when in upturned position, combined substantially as set forth.

7. A cooking stove comprising, an oven, a burner-pit extending along one side thereof, air-ports through the floor of the burner-pit, a valve-plate controlling said air-ports, a burner disposed in the burner-pit, a plate disposed removably in the base of the oven above the main floor thereof and over said burner-pit and adapted to slide into the oven lengthwise of said burner-pit, and mechanism connected with said valve-plate and adapted to be operated to open said air-ports when the plate disposed above the main oven floor is laid rearwardly into position, combined substantially as set forth.

8. A cooking stove comprising, an oven, a fire-box, a chimney-flue, a top flue leading from the fire-box over the oven, a vertical flue at that side of the oven opposite the fire-box, a horizontal flue leading under the oven from said vertical flue, a port leading from the top flue to the chimney flue, a port leading from the horizontal flue to the chimney-flue, a burner disposed at the base of the oven, a horizontal top flue comprehending the top of the oven, ports leading from the oven to said horizontal top flue, a port leading from the horizontal top flue to the chimney-flue, a flue structure placing said top flue in communication with said

vertical flue, a damper to control the port leading from the top flue to the chimney-flue, a damper to control the port leading from said horizontal top flue to the chimney-flue, and means for operating said dampers, combined substantially as set forth.

9. A cooking stove comprising, an oven, a fire-box, a chimney-flue, a top flue leading from the fire-box over the oven, a vertical flue at that side of the oven opposite the fire-box, a horizontal flue leading under the oven from said vertical flue, a port leading from the top flue to the chimney-flue, a port leading from the horizontal flue to the chimney-flue, a burner disposed at the base of the oven, a horizontal top flue comprehending the top of the oven, ports leading from

the oven to said horizontal top flue, a port leading from the horizontal top flue to the chimney-flue, a flue structure placing said top flue in communication with said vertical flue, a damper to control the port leading from the top flue to the chimney-flue, a damper to control the port leading from said horizontal top flue to the chimney-flue, 20 means for operating said dampers, and operative mechanism connecting said two dampers to cause them to open and close in unison, combined substantially as set forth. 25
